SACROILIAC BELT WITH CROTCH STRAPS

Filed July 31, 1951

UNITED STATES PATENT OFFICE

2,673,346

SACROILIAC BELT WITH CROTCH STRAPS

Ralph E. Davis, Milwaukee, Wis.

Application July 31, 1951, Serial No. 239,516

4 Claims. (Cl. 2—41)

1

This invention relates to a sacroiliac belt having crotch straps.

The principal object of the invention is to provide a sacroiliac belt with crotch strap means which prevents the belt from "riding up," but accomplishes this result without discomfort to the patient. A particular object of the invention is to locate these crotch straps so that they encircle the patient's legs below the patient's buttocks (the gluteus maximus muscle) in order that the belt may be comfortably worn, and particularly that the patient may move about and sit comfortably.

This invention consists in a belt having a rear band portion worn above the buttocks, and crotch straps having connections to the belt between which they at least partly encircle the patient's upper thighs, but lie below the buttocks.

In the drawings:

Fig. 1 is a front view of my improved belt as it appears in use, the outline of the patient's body being shown diagrammatically.

Fig. 2 is a side view of my improved belt as it appears in use, the outline of the patient's body being shown diagrammatically.

Fig. 3 is a plan view, on a reduced scale, of the open belt.

The sacroiliac belt indicated generally by the reference character 10 is of the type described in my prior Patent No. 2,543,095, issued February 27, 1951, and entitled "Sacroiliac Belt." The belt comprises a band 10 which encircles the body and has a central apex 11 disposed to rest over the patient's sacrum and above the buttocks or gluteus maximus muscle indicated by reference character 21. The belt has widening end portions 12 provided with stiffening means or lines of stitching 13 to which tension straps 14 and buckle straps 15 are anchored. In open plan the belt describes the form of a shallow V as shown in Fig. 2. When worn, the end portions 12 of the belt are downwardly inclined from the apex 11 to dispose the tension straps over the lower abdomen of the patient as shown in Figs. 1 and 2.

In order to securely anchor the belt against "riding up" I provide crotch straps 18. These are detachably connected with the belt, as by means of the snap fasteners 19 which are anchored to the lower margins of the end portions 12 of the belt. Second anchorages for the straps comprise buckles 20 anchored to the belt along the lower margin thereof but spaced somewhat toward the apex 11. Both anchorages thus lie forwardly of a transverse center line through the patient's body. The spacing of the buckles 20 from the

2

snap fasteners 19 is such that when the straps 18 are passed about the upper thighs of the patient, and connected to the buckles 20 the straps 18 will lie below the patient's buttocks or gluteus maximus muscles. As the belt 10 encircles the body substantially above the buttocks, no strap or belt passes over the buttocks. Accordingly, the belt may be worn for long periods of time, and the patient may seat himself and otherwise move about in complete comfort. The belt and straps are disposed over body portions which have little movement in the normal activity of the body, hence chaffing is reduced to a minimum.

As best shown in Fig. 1 the straps 18 constitute an extension of the lower margin of the belt. Accordingly, strap tension has no dislocating effect on the belt position. A properly positioned strap will follow the muscle fold between the buttocks and the leg.

I claim:

1. A device of the character described comprising a sacroiliac belt having at its ends tension straps for connecting the ends of the belt across the lower abdomen of the patient's body, in combination with first and second crotch strap connections, both of which are proximate the same end of the belt, the connection farthest from the end being inclined away from such end at an angle to the longitudinal center line of the belt, and a crotch strap attached to said connections in a position to at least partly encircle the upper thigh of the patient's leg between said connections, said strap extending from the connection farthest from the end of the belt downwardly to lie below the patient's buttocks and thence from between the patient's legs upwardly to the connection nearest the end of the belt.

2. A device of the character described comprising a belt having left and right forward end portions with detachable connecting means and having an intermediate portion adapted to be disposed at the rear of the patient's body and passing above the patient's buttocks, and a crotch strap having terminal connections to the belt both of which are attached to the same forward end of the belt, whereby to be forward of a transverse center line through the patient's body, said strap having a downward and rearward projection from one of said terminal connections, whereby to lie below one of the patient's buttocks and having an upward and rearward projection from between the patient's legs toward the other of said terminal connections whereby to encircle at least partially the upper thigh of the patient's leg between said connections.

3. The device of claim 2 wherein said connec-

tions are at the lower margin of the belt, the forward terminal connection comprising a pivot on which the strap is free to assume a position constituting an inward and rearward extension of said lower margin.

4. The device of claim 2 in further combination with a second crotch strap having terminal connections both attached to the other forward end portion of the belt and having a downward and rearward extent from one of its terminal connections whereby to lie below the patient's other buttock, and having an upward and rearward projection from between the patient's legs toward the other of its terminal connections, whereby to encircle at least partially the upper thigh of the patient's other leg between said terminal connec-

tions, the connection to which each strap extends upwardly and rearwardly as aforesaid comprising means for pivoting the respective strap terminals with reference to the belt end portions to which 5 they are respectively connected.

RALPH E. DAVIS.
